(57) **CLAIM**

I claim the ornamental design for an information display for electric car, as shown and described.

DESCRIPTION

FIG. 1 is a front perspective view of an information display for electric car of the present invention;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof;

FIG. 8 is a bottom view thereof;

FIG. 9 is a cross-sectional view taken along the line 9-9 in FIG. 3 with the internal parts being omitted;

FIG. 10 is a cross-sectional view taken along the line 9-9 in FIG. 3 with the internal parts being omitted, showing a state in which the information display unit is moved;

FIG. 11 is a cross-sectional view taken along the line 9-9 in FIG. 3 with the internal parts being omitted, showing a state in which the information display unit is moved; and,

FIG. 12 is a cross-sectional view taken along the line 12-12 in FIG. 6 with the internal parts being omitted.

The broken lines in the drawings represent portions of the information display for electric car that form no part of the claimed design. The dot-dash broken lines represents the bounds of the claimed designs and form no part of the claimed design.

1 Claim, 12 Drawing Sheets
